Primary Examiner — Zenia I Bennett*(74) Attorney, Agent, or Firm* — Ruggiero McAllister & McMahon LLC(57) **CLAIM**

The ornamental design for a hair dryer, as shown and described.

DESCRIPTION

FIG. 1 is a front perspective view of an ornamental design for a hair dryer according to the present invention; FIG. 2 is a front elevational view of the hair dryer of FIG. 1;

FIG. 3 is a rear elevational view of the hair dryer of FIG. 1; FIG. 4 is a left side elevational view of the hair dryer of FIG. 1;

FIG. 5 is a right side elevational view of the hair dryer of FIG. 1;

FIG. 6 is a top plan view of the hair dryer of FIG. 1; and, FIG. 7 is a bottom plan view of the hair dryer of FIG. 1. The broken lines shown in FIGS. 1-7 are for the purpose of illustrating environmental structure and form no part of the claimed design.
